[57] CLAIM

The ornamental design for a cattle halter, as shown and
described.

DESCRIPTION

FIG. 1 is a perspective view of a cattle halter showing
my new design;

FIG. 2 is a front elevational view thereof;

FIG. 3 is a rear elevational view thereof; and,

FIG. 4 is a side elevational view thereof, the opposite
side being substantially a mirror image of the side
shown.

FIG. 1

FIG. 2

FIG. 3

FIG. 4
